AUTOMATIC TELEPHONE SYSTEM

Application filed October 30, 1930, Serial No. 492,228, and in Great Britain November 13, 1929.

This invention relates to automatic or semi-automatic telephone exchange systems and is more particularly concerned with systems in which order wires are used. Order wires are 5 normally used between operators at different manual exchanges for the transmission of particulars of calls to be set up between the two exchanges.

Proposals, however, have also been made 10 whereby order wires are provided between automatic and manual exchanges. In these arrangements, an order wire to the wanted manual exchange is automatically taken into use during the setting up of a call from an automatic subscriber, and it is to such arrangements that the present invention relates.

According to one feature of the invention automatic to manual order wires comprise a single pair of conductors.

According to another feature of the invention, voice frequency currents are automatically sent over an order wire taken into use between an automatic and a manual exchange during the setting up to a call from the automatic exchange to the manual exchange.

According to a further feature of the invention, the order wire is adapted to transmit a busy signal from the operator at the manual exchange to the automatic exchange in response to an action on the part of the operator.

According to yet another feature of the invention a selecting stage in an automatic exchange is adapted to select one of a number 25 of groups of outlets in accordance with the path of access only.

In the embodiment of the invention to be described, the automatic exchange is of the common control by-path type, that is an exchange 40 in which each selected stage comprises a conversational switch of the finder type and a by-path switch over which the connection is primarily extended and which controls the setting of the conversational switch.

Fig. 1 of the accompanying drawings shows 45 the layout of the embodiment to be described. In setting up a call to a manual exchange an automatic subscriber dials the wanted subscriber's number. In response to the code 50 digits an outgoing selecting stage is reached

and the outgoing by-path switch R2 selects an idle outgoing repeater RP associated with which is an idle register RG. The remaining digits are dialled into the register and the outgoing conversational switch becomes connected to the repeater. An order wire or order wires is or are adapted to be connected to the register by a plurality of link circuits LC which are allotted for use in turn by link sequence distributor switch LD. This 55 switch determines that the calls to be set up over the particular order wire or order wires are extended thereto in strict order of arrival. When the register has been set a predetermined link circuit LC makes connection therewith and when the wanted order wire becomes 60 free connection is made between the order wire and the link circuit. A signal is now sent to the operator at the manual exchange who throws her listening key. The register 65 is associated with a common call announcing mechanism, and in response to the operator's action, the register controls the announcement of the wanted subscriber's number over the order wire to the operator's phones.

If the operator finds that the wanted subscriber is busy, she throws a busy key associated with the order wire. In response to this operation busy tone is sent to the calling subscriber from the register and the register 70 and order wire are automatically released. If, however, the call can be extended, the operator picks up a single ended cord individual to an idle one of a group of junctions from the automatic exchange and plugs into the 75 wanted line. This operation marks the junction in the banks of a finder switch CF associated with the repeater. The register is arranged so that at a predetermined interval after the announcement has been made, it 80 will initiate the hunting movement of CF; this interval is determined by the average time an operator will take to test and plug a wanted line. When the finder switch CF makes connection with the junction, the register 85 and order wire are released.

The same set of repeaters and associated registers can be reached from the outgoing selecting stage in response to a plurality of digits. In the particular embodiment, two 100

paths of access are commoned, a relay JJ being operated if one of these paths is used. In this case the register and switch CF will have access respectively to a plurality of order wires and groups of junctions to different exchanges or to different positions at the same exchange. In accordance with the path of access to the repeaters, an order wire in the desired direction is selected and the finder switch CF is made to hunt in the required group of junctions only. If the exchange to be reached is a tandem exchange it may be necessary to announce the name of the wanted exchange, in addition to the wanted subscriber's number. The register is arranged so that in accordance with the path of access thereto an exchange designation or some other suitable announcement may or may not be sent from the call announcer, or different designations may be sent. The path of access may in addition control the selection of different positions at the tandem exchange.

If split order wire working is in use at a manual exchange and order wires are incoming to the same position from manual and automatic exchanges, it is desirable, in order to retain uniformity of announcement that the name of the calling exchange should be announced from the automatic exchange. An announcement of the designation of the calling exchange can be made in the present modification.

Other features of the invention will be apparent from the particular description of this embodiment given below and are set out in the appended statement of claims.

Referring now to the accompanying drawings, Fig. 2A and 2B illustrate a repeater circuit which includes a non-numerical switch which permits the repeater to be used in conjunction with any one of a number of junction circuits.

The junctions terminating on this switch extend to two different exchanges or alternatively to two different operators' positions at the same exchange.

Figs. 3A and 3B show a register circuit which is associated with a number of the repeater circuits shown in Figs. 2A and 2B. The register is arranged to store four digits and is wired in multiple with other registers to a common announcing mechanism which announces various designations independently of the operation of any particular register circuit.

Fig. 4 shows an order wire link circuit which serves the purpose of connecting the register to the required order wire. A link sequence distributor also shown in Fig. 4 controls the sequence in which any particular order wire makes connection with registers waiting to announce a call.

Fig. 5 shows an order wire junction circuit modified to receive calls from an automatic exchange.

Fig. 6 shows an order wire junction circuit modified to receive calls from an automatic exchange.

The repeater and register circuits are tested and seized simultaneously over the test wire, contacts $h\cdot 1$, $br\cdot 1$, $hr\cdot 1$ of the repeater, contacts $bb\cdot 6$ and the home position and wiper $rm\cdot 32$ to battery. The operation of the testing relay in the preceding switching stage causes the impulsing circuit to be extended to the register to cause the operation of relay A. It should be understood that the testing circuit, which has been described, is used for any of the plurality of junctions which may be reached through the non-numerical stage associated with the repeater. When these junctions are leading to two different exchanges, it is necessary to make some discrimination in order that a junction in the proper group is selected. For this reason the register is arranged with a discriminating circuit operated by the path of access by means of which certain relays are operated. If, for example, the junctions lead to exchanges I and II it is assumed that the necessary discrimination is obtained by the office code digits received by the preceding switching stage and that whereas the relay A will be operated only when the exchange I is required, the relay JJ will be operated in series with the relay A when exchange II is required. The relay A closes the obvious circuit for relay B at $a\cdot 1$ and relay B closes the preceding by-path. The circuit for relay A is then maintained through contacts $bb\cdot 2$, $hr\cdot 2$, $br\cdot 3$, $dr\cdot 2$, the impulsing loop $dr\cdot 1$, $bi\cdot 2$, to ground. When the relay A responds to the dialling impulses a stepping circuit will be closed for the magnet RM3 through contacts $e\cdot 4$, $b\cdot 2$, winding of relay C, $a\cdot 1$, to ground. Relay C is of the slow releasing type and remains operated during the train of impulses. The switch RM3 will advance its wipers one step for each impulse received and when the relay C releases at the end of the train of impulses, a circuit will be closed from the battery and non-inductive resistance connected to the wiper $rm\cdot 32$ through the bank contacts in any of the positions 2-9, winding of relay Z, contacts $e\cdot 2$, $e\cdot 1$, $b\cdot 4$, to the wipers, $rm\cdot 33$, $rm\cdot 34$, $rm\cdot 35$, $rm\cdot 36$ and through the relative bank contacts to cause the operation of the combination of relays MA, MB, MC, MD which correspond to the digits dialled. Relay Z is operated in series with the storage relays MA, MB etc., but is slow to operate and consequently the storage relays will have closed their locking windings, through contacts $sz\cdot 1$ and $b\cdot 1$ to ground before the contacts $e\cdot 2$ open. The circuit is also provided when the relay Z operates for the magnet RM3 through its interrupter springs, contacts $e\cdot 1$, the bank contacts and wiper $rm\cdot 37$, to ground which causes the switch to step forward to position 10. The second train of impulses

cause a similar operation, the corresponding combination of the relays CA...CD (not shown) being locked up to store the digit dialled and the switch RM3 advances to position 20.

Should it happen that the thousands, and hundreds digits stored in the relays MA-MD and CA-CD are identical, a circuit will be extended from battery, wipers 10 rm32, bank contact 20, contacts *ca2*, *ma2*, *mb2*, *cb2*, *cc2*, *mc2*, *md2*, *cd2*, *c1*, *b4*, wipers 15 *rm33*, *rm34*, *rm35*, *rm36*, which will cause the operation of any of the relays MA-MD which were at that time unoperated. The third set of impulses operates a combination 20 of the relays DA-DD (not shown) and causes the switch RM3 to advance to position 30 while the fourth set of impulses causes a similar operation to the relays UA-UD 25 (not shown) and the switch RM3 advances to position 40.

Should it happen that the third and fourth digits were identical, a circuit would be closed through contacts *ua2*, *da2*, *db2*, *ub2*, 25 *uc2*, *dc2*, *dd2*, *ud2*, to cause the operation of any of the relays DA-DD which would otherwise remain unoperated.

In position 40 a circuit is also closed for the relay E and battery through the winding 30 of relay E, contacts *e1*, *bt2*, *sa7*, wiper *rm38*, *sa2*, to ground. Relay E locks over contacts 31 and *b1* to ground. Contact 12 closes a circuit for the magnet of the order wire link circuit LM from battery, winding of the magnet, 35 interrupter springs, contacts *tl2*, wiper *dm2* of the link sequence distributor, contacts *h2* and *e2* to ground. Contact *e3* prepares a testing circuit for the relay TL which will be operated when the wipers of the order 40 wire link circuit reach the bank terminals corresponding to the register in question. The circuit for relay TL will then be completed from battery, non-inductive winding of relay H, contact *h1*, *e3*, bank contact and 45 wiper *lm7*, inductive and non-inductive winding of the relay TL, wiper *dm1* of the link sequence distributor, to ground. Relay TL is equipped to operate and opens at *tl2* the driving circuit of the magnet LM closing 50 at the same time a circuit for the magnet DM through its own interrupter springs. The switch DM will take one step and open its own circuit at the wiper *dm2*. Contacts *tl1* close a locking circuit for the relay TL. Relay H has an inductive winding in multiple 55 with the non-inductive winding and operates from the ground at *tl1* after the relay TL has operated. Contact *h1* opens the non-inductive winding of relay H reducing the potential 60 on the bank contact of the wiper *lm7*; contact *h2* extends the starting ground through contacts *h2*, *jj5*, bank contact and wiper *lm5* (or *lm6*) to the relay N of the outgoing order wire. Contacts *h3* place a marking 65 potential on the bank contact and wiper

lm3 (or *lm4*) through contacts *jj4*. When the relay N operates as already described a circuit is prepared for the magnet OWM through contacts *n1* and *p1* to ground so that when the order wire falls free the order wire 70 switch OWM will step forward until its wiper *owm3* makes contact with the terminal marked by the contact *h3* of the next waiting link which will be assumed to be that shown. In this position the relay P will operate opening the stepping circuit of the magnet OWM 75 and closing the obvious circuit for relay PP at contacts *p1*. Relay PP provides a locking ground for relay P at contacts *pp3* and prepares at *pp2* a portion of the announcer 80 circuit. Relay K operates in series with relay P and opens at *k2* the operating circuit of relay N. Contacts *k1* open the non-inductive winding of the relay K to reduce the potential on the bank contact and wiper 85 *owm3*; contacts *k3* transfer the operating circuit of the relay BB through contacts *bb1* and *p2* over the order wire, through the busy and listening key through the relay LN, to ground. Relay LN operates and lights a 90 calling lamp CL. When the relay H operated a circuit was prepared for the relay G, contacts *jj3*, *kr8* (or *kr9*) wiper *cfm2* (or *cfm4*). If the switch CFM is standing on a set of terminals leading to exchange I and the relay JJ has been operated to indicate that the call is going to exchange II, a circuit will be completed for the relay G over the wipers *cfm4* and in a similar way if the switch CFM is standing on a set of terminals 95 leading to the exchange II and the relay JJ has not been operated because the call has to be extended to the exchange I, then a circuit will be completed for relay G over the wiper *cfm2*. It will be understood that ground is connected to the bank terminals associated with wiper *cfm2* on those outlets leading to exchange II whereas ground is connected to the bank contacts associated with the contacts 100 *cfm4* on those outlets leading to junctions extending to exchange I.

The operation of relay G closes the stepping circuit of the magnet CFM through its interrupter springs, *kr3*, *g1*, *m1*, *b1*, to ground causing the switch CFM to continue stepping 115 as long as the relay G remains operated. Hence the switch will be driven round to the first junction to the required exchange. Contact *h5* closed a circuit for relay W through contacts *sz4* and relay W consequently closes 120 a circuit for relay Y through contacts *w1*.

When the operator throws her listening key she opens the circuit of relays BB and LN: Relay BB prepares at *bb2* a circuit for the relay SA over contacts *h4*, *sz2*, *bb2*, to a starting cam which is connected to ground and associated with the announcing mechanism. When the cam completes the circuit relay SA operates and locks over its second winding and contacts *sa1* to a second cam. 125 130

Contact *sa7* closes a circuit from ground through the repeating coil in the order wire, contacts *pp2*, wiper and bank contact *own1*, the wiper and bank contact *lm1*, contact *sa2*, 5 wiper and bank contact *rm38*, contact *sa7*, *jj6*, to the announcing mechanism. In this position arrangements can be made to send to the B operator the name of the exchange to which the call is to be transmitted if it is 10 desired to tandem the call. If the call is for a subscriber connected to the exchange served by the B operator, it will be unnecessary to announce any terminating exchange. As already explained, the relay *SA* is held operated 15 by a cam on the announcing machine and this device prevents the relay *SA* operating to clip an announcement. The operation of relay *SA* also closes the circuit for the magnet *RM3* through contacts *sa7*, bank contact and wiper 20 *rm37*, to ground and when the relay *SA* releases at the end of the preliminary announcement, the switch *RM3* advances one step. Relay *SA* reoperates and the order wire is connected through contacts *sa6*, *ma3*, and the 25 particular combination of relays *MB*, *MC* and *MD* indicating the thousands number to the announcing mechanism. At the end of the first announcement, relay *SA* releases advancing the switch *RM3* to position 42 in 30 which position the hundreds digit is announced. In position 43 no announcement is made in order to provide a pause between the hundreds and tens digits. In positions 44 and 45 the tens and units digits are announced respectively.

Should it happen that all the four relays *MA*—*MD* or *DA*—*DD* are operated, the order wire will be connected through contacts *sa6* or *sa4* to a terminal of the announcing 40 mechanism which will announce the word "double". Consequently if, for example, the number 4477 is dialled, the announcement will be "double 4, double 7" but if the number 4774 is dialled, the number will be announced in 45 the ordinary way.

The announcements are repeated over the order wire to the operator's telephone circuit and on completion, the B operator will test the required subscriber's line. If the line 50 is busy, the B operator will throw the busy key associated with the order wire thereby connecting battery to the order wire which will be extended over contacts *p2*, wiper and bank contact *own2*, wiper and bank contact *lm2*, 55 contacts *bb1*, to the winding of relay *BT* and ground. The operation of relay *BT* will cause the operation of relay *BR* in the repeater by the contacts *kr5*, *e5*, *bt1*. Relay *BR* introduces the relay *AR* over the subscriber's loop 60 and contacts *br2*, *dr1*, *dr2* and *br3*. Relay *AR* provides a holding circuit for the relay *BR* at *ar1* and busy tone is passed to the calling subscriber through the tone condenser, contacts *ar2*, *hr3* and the talking condenser to 65 the subscriber's loop. The operation of relay

BR also releases relay *A* as described below to release the register.

If the required subscriber's line is free, the B operator will insert the calling plug thereby causing the operation of relay *S* 70 from battery, supervisory lamp *SL*, winding of the relay *S*, sleeve of the plug and jack, to ground. The supervisory lamp *SL* will light and a circuit is prepared for ringing the required party through the contacts *s1*. 75 At *s2* a ground is extended through contacts *rr2* and one side of the repeating coil to the positive leg. This ground potential forms a signal to the automatic office to indicate which cord circuit has been selected by the B operator.

Meanwhile the switch *RM3* has been caused to advance to position 50 due to the intermittent operation of relay *SA*; this time interval has been inserted so that switch *CFM* 85 should not begin to hunt before the B operator has seized a junction. In position 50 a circuit is closed for relay *SZ* over the bank contact and wiper *rm38*, contacts *sa2*, to ground. Relay *SZ* opens at *sz2* the operating 90 circuit of the relay *SA* to prevent that relay operating again. Contacts *sz1* open the locking circuits of the various storage relays *MA*—*MD* etc. It will be remembered that relays *W* and *Y* were operated when the 95 relay *H* operated. The operating circuit of relay *W* is opened by contact *sz4* and this relay releases thereby opening the circuit for relay *Y* which also releases. When relay *Y* has restored a circuit is reclosed for the 100 relay *W* through contacts *h5*, *sz4*, *y2*, *m1*, *b1* to ground. Relay *W* is, however, slow to operate and during this period a circuit is prepared for the relay *M* through contacts *y1*, *g3*, *sz5*, *kr7*, the positive wiper *cfm1*, to 105 the junction line on which the switch *CFM* is standing. If this junction is not the one selected by the operator, relay *M* cannot operate and after the relay *W* has operated, relay *Y* will operate opening the circuit of 110 the relay *M*. Relay *Y* is also slow to operate and during the period of this operation a circuit is closed for magnet *CFM* through contacts *kr4*, *sz3*, *w3*, *y3*, *m1*, *b1*, to ground. This circuit is opened at *y3* at which time the 115 magnet takes one step forward. Contacts *y2* open the circuit of relay *W* which will release unless maintained by the contacts *g2*. Relay *G* has a possible circuit through contacts *h4*, *jj3*, *kr8* (or *kr9*) and the wiper *cfm2* (or *cfm4*) to ground extended to the bank contacts by the contacts *h2* (or *h5*) of some other repeater switch. This ground potential will exist if the junction line on 120 which the switch *CFM* is standing is engaged and the operation of the relay *G* besides maintaining the circuit of relay *W*, as already explained, will close an operating circuit for the magnet *CFM* through its interrupter springs, contacts *kr3*, *g1*, *m1*, *b1*,

125 130 135 140

to ground. In this way the switch CFM will be caused to step immediately over any junction which is in use and to test each disengaged junction by connecting the relay M 5 to the positive leg of the junction. When the junction selected by the B operator is reached, relay M will be operated and a locking circuit will be closed immediately through contacts m_1 , b_1 , to ground.

10 Relay M closes at its contacts m_2 a circuit for the relays HR and BR through contacts kr_6 and through contacts bt_1 , e_5 , kr_5 . The relay BR introduces the relay AR as already explained, whereas the relay HR opens the 15 busy tone circuit at hr_3 and closes at hr_4 a circuit from ground through relay ER, contacts br_5 , negative side of the junction, one side of the repeating coil, winding of relay L to battery. Relay ER provides a locking 20 circuit for the relay HR at contacts er_1 , and prepares at er_2 , a circuit for the relay DR. Relay L in the B cord circuit shunts the supervisory lamp SL through contacts l_1 , tr_1 , rr_1 , the negative and non-inductive wind- 25 ings of the relay R in multiple to battery. Relay R will operate introducing the ringing supply through the ringing relay TR, contacts r_1 , s_1 , subscriber's loop contacts r_2 , to ground. While the ringing is taking place 30 the register will release due to the fact that the operation of contacts br_3 open the circuit for the relay A. Relay A opens at a_1 , a circuit for relay B. Relay B opens at b_1 a fundamental ground circuit permitting the 35 remaining relays to release. The switch RM3 steps to its home position through its interrupter springs, contacts bb_5 , b_3 , sa_7 , bank contact 50 and the wiper RM37, to ground. The opening of contacts bb_6 causes 40 the release of the relay KR but the repeater is maintained busy because the test circuit is held open by contacts hr_1 , and br_1 . Contacts hr_2 and hr_5 maintain a ground potential on the bank contacts corresponding to the junction 45 taken into use to prevent intrusion. When the called subscriber replies the relay TR trips opening the short circuit around the relay RR and this relay operates in series with the relays R and S. Contacts rr_1 , short 50 circuit the relay R which now releases switching over at contacts r_1 and r_2 the subscriber's loop from the ringing supply to the talking bridge and thereby causing the operation of the relay CS. Contacts rr_2 and cs_1 connect 55 battery potential to the positive side of the junction thereby causing the operation of relay DR in the repeater through contacts hr_3 and er_2 . Relay DR reverses the battery supply to the calling subscriber over contacts 60 dr_1 and dr_2 and the connection is now established.

After the B operator has inserted her plug it is essential that she does not receive a further call until the first connection has 65 been completed between the outgoing re-

peater and the junction and on this account the order wire circuit is locked to the register by relay P which remains operated in series with relay K so long as the relays H and E remain operated. When the relay AR in the 70 repeater operates and releases the register the order wire and order wire link circuits are also released and the order wire makes connection with any other register which has a call awaiting announcement. Such a condition would be signalled by the fact that a 75 register had made connection with an order wire link circuit thereby placing ground potential on the wiper lm_5 of the latter causing the operation of the relay N. It should be understood that all calls to be announced to a particular distant exchange will be stored 80 in sequence in order wire link circuits allocated to that particular junction group. Should the junction group be sufficiently 85 large to justify the use of two order wires, both OWM switches will search over the same group of order wire link circuits, the waiting calls being handled in rotation. The use of the discrimination offered by the relay JJ 90 may be extended to the order wire link circuit to enable these circuits to be common to two exchanges. The starting signal and testing condition is duplicated over the wipers lm_3 and lm_5 , lm_4 and lm_3 . 95

During the time the switch CFM is hunting for the junction chosen by the operator a tone is connected through the bank contact and wiper lm_2 , bank contact and wiper owm_2 , contacts p_2 , both sides of the order 100 wire to the operator's telephone circuit in order that the operator may know the condition at the automatic exchange and if necessary change the cord circuit.

Should the operator fail to dial the necessary digits into the register or delay the dialling beyond some predetermined period, an alarm will be given in the following manner:—When the relay BB operated, a circuit 105 was extended from battery, one winding of the relay BT, the wiper and home position rm_31 , contacts bt_3 , and bb_4 to an "A" pulse circuit. BT provides a locking circuit for itself through contacts bt_3 to ground at b_1 . Should the subscriber fail to dial, relay E 110 will be operated from battery, winding of relay E, contacts e_1 , bt_2 , to a "Z" pulse circuit, it being arranged that the "Z" pulse follows the "A" pulse after some fixed period of time. The operation of relays E and BT 115 close a circuit for the relay BR as is previously described. Relay BR introduces relay AR and applies busy tone. Relay BR also releases the register. A similar circuit 120 for the relay BT is established in positions 10, 20 and 30 in case delay may occur before the hundreds, tens or units digits. In position 50 the "A" pulse circuit is connected through contacts ss_6 , e_2 , the winding of relay e , bank contact 50 and wiper rm_32 to bat- 125 130

tery. Relay Z locks at z_2 and prepares a circuit over contacts z_3 for the "Z" pulse circuit to the relay BT. If the relay BT operates in position 50, BR in the repeater will be 5 operated as already described, relay E having been operated in position 40 and locked up. The circuit for the switch CFM is arranged so that it will hunt continuously, stepping over all engaged junctions or junctions 10 leading to a second exchange without testing and the use of the time pulse circuits in position 50 serves to release the register and the B operator, if the switch CFM fails to find the junction selected within some predetermined 15 period. It will also be seen that the B operator can apply the busy tone by operating the busy key at any time, such an operation causing BT to operate BR and release the register.

20 When the calling subscriber releases relay AR falls back and opens the circuit for the relay BR. Contacts br_4 remove the holding ground from the hold wire permitting the preceding switches to release. The relays 25 ER and DR remain operated to the B cord circuit. When the called subscriber releases, relay CS falls back disconnecting the battery from the positive side of the junction and thereby opening the circuit of relay DR. Relay DR opens at contact dr_3 the circuit for relays ER and L. Relay ER opens at er_1 a circuit for relay HR and relay L opens at contacts 11 a circuit for relay RR and re-introduces the supervisory lamp SL. Relay 30 RR connects ground to the positive wire, through contacts rr_2 and s_2 thereby providing a holding circuit for relay HR until the operator pulls out the plug permitting relay S to release.

35 If it is desired to use a split order wire position, one relay LN will be provided for each office terminating in the split position. Each relay LN will be provided with its own calling signal and key. It is possible, therefore, for a split position to operate certain junctions from manual exchanges and others from automatic exchanges. Where necessary it will be arranged that the switch RM3 40 will announce the calling exchange name in position 40. This procedure will maintain the same conditions for the B operator when receiving calls from manual and automatic exchanges.

45 50 55 What is claimed is:

1. A telephone exchange system comprising an automatic exchange and a manual exchange, a two-wire order wire between said exchanges, register means for automatically selecting said order wire when a call is from an automatic exchange to a manual exchange, means by which signals indicative of a wanted subscriber's designation are transmitted automatically from said register over the order wire, and means for releasing said

order wire when connection with the manual exchange has been made.

2. A telephone exchange system comprising an automatic exchange and a manual exchange, junctions and an order wire extending between the two exchanges, register means controlled during the setting up of a call from a subscriber at the automatic exchange to the manual exchange to automatically select an order wire and means controlled by said register means for automatically sending voice frequency currents over said order wire to announce the wanted number to an operator at the manual exchange.

3. In a telephone exchange system, an automatic exchange and a manual exchange, junctions and an order wire extending between the two exchanges, register means controlled during the setting up of a call from a subscriber at the automatic exchange to the manual exchange for automatically selecting an order wire, means controlled by said register means for automatically sending voice frequency over said order wire, and means associated with the order wire to transmit back a busy signal from the manual exchange to the automatic exchange.

4. In a telephone exchange system, an automatic exchange and a manual exchange, a group of trunks between said exchanges, an order wire between said exchanges, a plurality of digit registers associated with the trunks outgoing from the automatic exchange to the manual exchange to store the numerical portion of the wanted subscriber's designation, means for connecting a register to an order wire, and a call announcing mechanism associated with the said plurality of registers to announce the wanted subscriber's designation over the order wire under the control of the register to which the order wire is connected.

5. A telephone exchange system comprising an automatic and manual exchange, a group of repeaters at the automatic exchange having access to junctions extending to one or more manual exchanges, order wires extending to said manual exchanges, registering mechanism adapted to record a wanted number associated with said repeaters, means controlled by said register mechanism to transmit an indication thereof over an order wire extending to a manual exchange, and means provided for operatively associating said registering mechanism with a predetermined one of said repeaters to the exclusion of the remainder.

6. In a telephone exchange system, an automatic selecting stage, different paths of access to said stage, a plurality of groups of outlets selectable at said stage, means for controlling the selection of said outlets depending upon the path of access to said stage.

7. A telephone exchange system, comprising step-by-step switches, a selecting stage, a

plurality of groups of outlets selectable at said stage, means for transmitting impulses to said switches, and means for controlling the selection of said outlets independent of 5 said impulses.

8. In a telephone exchange system, an automatic exchange and a plurality of groups of junctions leading to manual exchange, an outgoing numerical stage at the automatic exchange, a group of trunks, the outgoing numerical stage of the automatic exchange is adapted to be seized via a plurality of paths of access from said stage equal in number to 10 said junction groups, and means controlled at 15 said numerical stage to select a trunk which is in turn connected to a junction in a particular one of the groups of junctions in accordance with the path of access to said trunk.

9. A telephone exchange system comprising 20 an automatic exchange and a plurality of groups of junctions leading to manual exchanges, a numerical selecting stage at the automatic exchange, trunk circuits, means controlled at the numerical selecting stage at 25 the automatic exchange to select said trunk circuits and associating them in common with a plurality of groups of junctions.

10. In a telephone exchange system comprising 30 a group of trunk circuits associated with a group of digit registers, a selector stage and a plurality of paths having access thereto, means whereby any one of said circuits can be reached over a plurality of paths of access from a selector stage, and means to 35 extend it to any one of a number of groups of trunks or junctions equal in number to the paths of access.

11. In a telephone exchange system, an outgoing numerical selecting stage at an automatic exchange, a selecting stage and a plurality of paths having access thereto, a group of trunks associated with a group of registers outgoing from the automatic exchange and adapted to be reached over a plurality 45 of different paths of access from said selecting stage, a group of registers associated with said trunks, a plurality of groups of junctions outgoing from the automatic exchange to a number of manual exchanges equal in 50 number to the said paths of access, a plurality of order wires from said automatic exchange to said manual exchanges, means whereby a register taken into use in setting up a connection is automatically connected to 55 an order wire outgoing in a predetermined direction in accordance with the path of access to the register, and means whereby the outgoing trunk which is also used in the connection is automatically connected to the outgoing end of a particular junction which has 60 been taken into use at its incoming end at the manual exchange reached over the order wire.

12. A telephone exchange system comprising 65 an automatic exchange and a plurality

of groups of junctions extending to two or more manual exchanges, single motion switches at said automatic exchange, and means controlled by said switches which are adapted to extend connection to a junction 70 of a wanted group by the exercise of a hunting operation only.

13. A telephone exchange system comprising 75 an automatic exchange and a plurality of groups of junctions extending to two or more numerically different positions at the same exchange, single motion switches at said automatic exchange, and means controlled by said switches which are adapted to extend connection to a junction of a wanted group 80 by the exercise of a hunting operation only.

14. In a telephone exchange system, the combination of an automatic and a manual exchange, an outgoing selecting stage at the automatic exchange, a trunk circuit and an associated register, means at said selecting stage to select said trunk circuit, an order wire, means for connecting said register with said order wire to the manual exchange, a call announcing device common to a plurality of 85 registers, and means for connecting said device to said register for announcing the wanted number over said order wire.

15. A circuit arrangement as claimed in 90 claim 3 characterized in this that in response to said signal busy tone is connected to the calling subscriber.

16. A circuit arrangement as claimed in 95 claim 3, characterized in this that in response to said signal, the order wire is automatically 100 released.

17. A circuit arrangement as claimed in 105 claim 3, characterized in this that in response to said signal, the register is automatically released.

18. A circuit arrangement as claimed in 110 claim 4, characterized in this that calls incoming to the group of registers are connected to the order wire to the wanted exchange in their order of arrival.

In witness whereof, we hereunto subscribe our names this 18th day of September 1930.

ESMOND PHILIP GOODWIN WRIGHT.
LESLIE BAINES HAIGH.
